CHRISTIAN ALFRED PETERSEN, OF BEVERLY, MASSACHUSETTS.

SHOCK-ABSORBER.

1,135,391.

Specification of Letters Patent. Patented Apr. 13, 1915.

Application filed December 31, 1913. Serial No. 809,789.

To all whom it may concern:

Be it known that I, CHRISTIAN A. PETERSEN, a citizen of the United States, residing at Beverly, in the county of Essex and State of Massachusetts, have invented a new and useful Shock-Absorber, of which the following is a specification.

This invention has reference to improvements in shock absorbers, and while it may be used wherever applicable it is designed 10 particularly for use in connection with an automobile.

The object of the invention is to provide a means which shall become progressively 15 more resistant to a force to counteract the effect of the force with correspondingly increased effect.

In accordance with the present invention there is provided a spring-controlled member 20 responsive to the action of a force acting in opposition to the normal tendency of the spring, and this spring-controlled member has brake members associated therewith in a manner to rapidly multiply the resistance 25 to the force to be retarded, so that the effect may be far more rapid than would be the case were the resisting effect of the spring wholly relied upon.

The invention will be best understood 30 from a consideration of the following detailed description, taken in connection with the accompanying drawings forming a part of this specification, with the further understanding that while the drawings show 35 a practical form of the invention, the latter is not confined to any strict conformity with the showing of the drawings, but may be changed and modified so long as such changes and modifications mark no material 40 departure from the salient features of the invention.

In the drawings:—Figure 1 is an elevation of the device in a condition of repose. Fig. 2 is a longitudinal section with some 45 parts in elevation and showing the device in the active position of retarding the effect of a force exerted thereupon. Fig. 3 is an end elevation of the device as seen from the right hand end of Fig. 1. Fig. 4 is an elevation of a portion of the structure with 50 some parts shown in elevation and other parts omitted. Fig. 5 is an elevation, with parts in section, of one of the brake members. Fig. 6 is a section on the line 6—6 of 55 Fig. 2.

Referring to the drawings, there is shown

a frame 1 which may be a skeleton frame for lightness, and at opposite ends but projecting from the same face of the frame, are bosses 2, while at an intermediate point the 60 frame is formed with a sleeve 3 and between this sleeve and the bosses 2 are openings 4 through the frame.

Adapted to the sleeve 3 is a rod or bar 5 having one end 6 tapering with opposite 65 faces 7 preferably flat, while at the other end the bar 5 is expanded into a head 8 shown as having the face 9 remote from the bar rounded.

Each boss 2 is provided with a passage 10 70 through which is passed a pivot pin 11 traversing spaced ears 12 of a brake member 13, and this brake member may, like the frame 1, be of skeleton form with terminal 75 outstanding rounded portions 14, 15, respectively.

Surrounding the rod 5 between the sleeve 3 and head 8 is a spring 16 tending at all times to move the head 8 away from the sleeve 3. The taper end 6 of the bar 5 is 80 traversed at an appropriate point by a stop pin 17 which may be in the form of a cotter pin, or any other means serving as a stop may be provided.

Made fast at an intermediate point to the 85 head 8 by a screw 18 or otherwise is a strap 19, this strap being usually a leather strap, but any other strap or band may be employed. The ends of the strap on opposite sides of the head 8 are threaded through 90 respective passages 4 and about the bosses 2 which are curved on the faces engaged by the strap, and then the ends of the strap are carried between the side members of the frame 13 and about the rounded faces of 95 the portions 14, the ends of the strap extending to suitable points. In an automobile one end of the strap is secured to the axle or other part of the running gear, while the other end of the strap is made 100 fast to the body part of the vehicle.

When the vehicle, which may be assumed to be an automobile, is at rest, the normal action of the main springs of the vehicle may cause some compression of the spring 105 16. Suppose that the vehicle is traveling and that the wheels of the vehicle engage some obstruction which will cause a compression of the main springs of the vehicle. Under these circumstances the strap 19 is 110 slackened, and the expansion of the spring 16 causes a movement of the bar 5 in a direc-

tion to take up the slack of the strap, and this movement may continue until the stop 17 is brought into engagement with the frame 1, the main springs of the vehicle taking care of the shock. Immediately thereafter the main springs of the vehicle expand, thus moving the body and running gear apart and the movement if unimpeded is often violent enough to do damage either 10 to the occupants of the vehicle or to the main springs of the vehicle. As soon as the rebound of the main springs of the vehicle takes place this movement is participated in by the strap 19 which moves about 15 the bosses 2 and acts upon the head 8 to force the bar 5 in a direction to compress the spring 16, thus resisting the rebound of the main springs of the vehicle. At the same time the pull of the strap 19 acts upon the 20 ends 14 of the brakes 13, the strap ends each having a tortuous or indirect path around the ends 14 tending to rock these brakes upon the pivot pins 11 in a direction to force the ends 15 toward the frame 1. This 25 movement, however, is resisted by the tapered end 6 of the bar 5 introduced between the ends or heads 15 which operate as bearing shoes and continued movement of the bar 5 in the direction assumed tends to and 30 actually does rock the brakes 13 in the direction to force the ends or heads 14 more firmly against the strap 19 and cause it to bind with greater force upon the bosses 2, as well as upon the heads 14. There is therefore an impeding force to the movement of 35 the strap 19 caused by the rebound of the vehicle body represented by the resistance of the spring 16 and the frictional resistance of the heads 14 and bosses 2 to the movement 40 of those portions of the strap which pass between these members. Furthermore, the frictional resistance caused by the engagement of the heads 15 with the surfaces 7 of the tapered end 6 offers a material 45 resistance to the movement of the bar 5 under the pull of the strap 9. All these resisting forces increase progressively as the vehicle body rebounds, and while the resistance is relatively gradual it very quickly becomes 50 sufficient to arrest the rebound of the vehicle body before it assumes dangerous proportions either to the occupants of the vehicle or to the vehicle springs. The shock absorber may be supported wholly by the 55 strap 19 and is therefore in the nature of a floating device requiring no fastening means except those necessary for the attachment of the ends of the strap 19 to the running gear and vehicle body respectively.

60 The resistance to shock is both elastic and frictional, the elasticity of the shock absorber presenting a yielding resistance to the forces it is intended to overcome, while the frictional resistance of the shock absorber becomes progressively greater so

rapidly that even under the most severe conditions the rebound is neutralized before it can possibly become excessive, but still permits the normal action of the springs of the vehicle to an extent similar to the action of 70 these springs productive of easy riding.

What is claimed is:—

1. A shock absorber for vehicles, comprising a flexible member adapted to be attached at the ends to the parts of the vehicle to be 75 controlled, and means resistant to separating movements of the said parts of the vehicle and carried wholly by the flexible member.

2. A shock absorber for vehicles, comprising a flexible member adapted to be connected at opposite ends to relatively movable parts of a vehicle, and brake means in position to engage the flexible member to retard its movement, said brake means being connected to and wholly sustained by the flexible 85 member.

3. A shock absorber for vehicles, comprising an elongated flexible member, a rod connected to said flexible member intermediate of its ends, a frame through which the rod 90 extends, a spring on the rod between the ends thereof and in position to engage the frame, and brake members carried by the frame in coactive relation to the flexible member and to the rod. 95

4. A shock absorber for vehicles comprising an elongated flexible member, a rod connected at one end to an intermediate part of the flexible member and at the other end tapering, a frame traversed by the rod adjacent to the tapered end of the latter, a spring mounted on the rod between the frame and the end of the rod fast to the flexible member, brake members mounted on the frame on opposite sides of the rod and having adjacent ends in coactive relation to the tapered portion of the rod and at the other ends arranged to engage the flexible member. 100

5. A shock absorber for vehicles comprising an elongated flexible member, a rod connected at one end to an intermediate part of the flexible member and at the other end tapering, a frame traversed by the rod adjacent to the tapered end of the latter, a 115 spring mounted on the rod between the frame and the end of the rod fast to the flexible member, brake members mounted on the frame on opposite sides of the rod and having adjacent ends in coactive relation to the tapered portion of the rod and at the other ends arranged to engage the flexible member, the frame and those ends of the brake members remote from the rod being coactively shaped to there engage the 120 flexible member on respectively opposite faces thereof. 125

6. A shock absorber for vehicles comprising an elongated strap, a rod having one end tapered and at the other end formed with 130

- 5 a head to which the strap is connected at an intermediate point of its length, a frame having rounded bosses at opposite ends, and a collar or sleeve at an intermediate point with openings on opposite sides of the collar with the rod traversing the sleeve, a spring mounted on the rod between the sleeve and the head end of the rod, a stop member on the tapered end of the rod to limit the expansive movement of the spring, and brake members having opposite ends rounded and each pivoted on a respective boss of the frame with adjacent rounded ends engaging the tapered end of the rod and the other rounded ends adjacent to the respective bosses, the strap being threaded through the openings in the frame and about the bosses and corresponding ends of the brake members in coactive relation to both. 10
- 10 7. A shock absorber for vehicles comprising an elongated strap, a rod having one end tapered and at the other end formed with a head to which the strap is connected at an intermediate point of its length, a frame having rounded bosses at opposite ends, and a collar or sleeve at an intermediate point with openings on opposite sides of the collar with the rod traversing the sleeve, a spring mounted on the rod between the sleeve and the head end of the rod, a stop member on the tapered end of the rod to limit the expansive movement of the spring, and brake members having opposite ends rounded and each pivoted on a respective boss of the frame with adjacent rounded ends engaging the tapered end of the rod and the other rounded ends adjacent to the respective bosses, the strap being threaded through the openings in the frame and about the bosses and corresponding ends of the brake members in coactive relation to both, the strap constituting the sole support for the other parts of the shock absorber. 15
- 15 8. A shock absorber comprising a strap, a wedge member carried by the strap at an intermediate part thereof, and brake members supported by the wedge member and engaged by the wedge portion thereof and having parts in coactive relation to the strap to frictionally retard it. 20
- 20 9. A shock absorber comprising a strap, a wedge member carried by the strap at an intermediate part thereof, and brake members supported by the wedge member and engaged by the wedge portion thereof and having parts in coactive relation to the strap to frictionally retard it, the wedge member being provided with spring means tending to move the wedge member in a direction to withdraw it from between the brake members. 25
- 25 10. A shock absorber comprising a flexible member, spaced brake means tending to retard the movement of the flexible member in one direction, and elastic means associated with the flexible member between the spaced brake means, said elastic means being resistant to the stated movement of the flexible member and tending to move the flexible member in the opposite direction. 30
- 30 11. A shock absorber comprising a flexible member, spaced brake means tending to retard the movement of the flexible member in one direction, and elastic means also resistant to the same movement of the flexible member and tending to move the flexible member in the opposite direction, the brake means including means constructed to act with progressively increasing braking force during the first named direction of movement. 35
- 35 12. A shock absorber comprising a flexible member, elastic means for resisting the movements of the flexible member in one direction and tending constantly to move it in the other direction, and brake means active to the flexible member on opposite sides of the brake means and constructed to resist movements of the flexible member with progressively increasing force when the flexible member is moved in a direction opposed to the normal tendency of the spring means. 40
- 40 13. A shock absorber for relatively movable structures, comprising a connecting member adapted to be made fast to both structures, elastic means and friction means separately engaging the connecting member and constructed to coactively resist movements of said connecting member in one direction, and the elastic means having a normal tendency to move in a direction to release the connecting member from the friction means. 45
- 45 14. A shock absorber for relatively movable structures, comprising a flexible connecting member adapted to be made fast to both structures, elastic means fast to an intermediate portion of the connecting member, and friction means engaging the connecting member, said elastic and friction means being constructed to coactively resist movements of said connecting member in one direction and the elastic means having a normal tendency to move in a direction to release the connecting member from the friction means. 50
- 50 15. In testimony that I claim the foregoing as my own I have hereto affixed my signature in the presence of two witnesses. 55
